SWING FRAME CHANGING RING

Sandor A. Wittmayer, New York, N. Y.

Application November 25, 1949, Serial No. 129,342

9 Claims. (Cl. 63—15)

1

This invention relates to jewelry and particularly to rings with changeable tops, whereby an ornamentation on a ring or the displays thereon, like initials, Masonic emblems, and the like, may be changed from one to another, and this invention has for its main object to provide a ring of this character, of improved construction and operation.

Another object of my invention is to provide a ring as characterized hereinbefore, which will change automatically in one direction and which may be changed in another direction in an easy simple and quick manner.

Still a further object of this invention is to provide a ring carrying a plate having two different designs at the two sides thereof which plate is swingable in a frame and said frame itself is pivoted and swingable on the top of the ring.

Still a further object of my invention is to provide a ring of the type indicated which will have a flat base on its top and spring means to cause the changing ornamentation element to flatten on said base, said spring also having a tendency to turn said element in a predetermined direction.

Other objects of this invention will be apparent as the specification of the same proceeds, or will be pointed out therein, and, among others, I may mention: to provide a ring of the various advantages and novel features indicated, which will be attractive in appearance, novel and interesting in operation, and the design of which may be changed without removing it from the finger of the user.

In the drawings forming a part of this specification and accompanying the same:

Fig. 1 is a perspective view of a ring constructed according to my invention, the swingable frame on the top being in an open position to indicate the manner of changing the design in the top of the ring;

Fig. 2 is a plan view of the ring showing as an example, a Masonic emblem thereon;

Fig. 3 is a rear view of my ring, and

Fig. 4 is a fragmentary front view, each of these views showing the ring with its swingable plate and frame in a flat position, folded and locked thereon;

Fig. 5 is a fragmentary detail on a larger scale showing the arrangement of a coil spring with the pin for the swingable plate, and

Fig. 6 is a fragmentary sectional view on a smaller scale of the top of my ring, its swingable frame being shown in an open position.

2

Referring now to the drawings more in detail, by characters of reference, the numeral 10 indicates my novel ring, in general, having the ring proper 11 and a flat top portion 12 for the same. Upstanding rims 13 and 14 are at the two sides of the flat top 12, each having semi-circular depressions 15 for the purpose to be more fully described hereinafter.

A pivot device 16 of any appropriate construction is arranged at the rear side of the flat top 12 and on said pivot is rockable or swingable a frame 17, said frame is adapted to be closed on its pivot 16 down on the flat top 12 of the ring snugly fitting between the side rims 13 and 14.

A swingable plate 18 is arranged in the frame 17 rotatable on the pins 19 arranged in the projections 20 in the two sides of the frame. When the frame is closed down upon the flat top 12 of the ring, the outer ends of the projections 20 will rest in the depressions 15, the plate 18 snugly fitting within the frame 17 and carrying two different ornamentations or designs on its two sides.

In the embodiment shown, at one side, indicated by the numeral 21, it carries initials 22, while at the other rear side 23 thereof, which is shown in Fig. 2, it carries a Masonic emblem 24.

A coil spring 25 may be arranged around one of the pins 19, as indicated in the fragmentary view of Fig. 5, one end of the spring engaging a part of the frame 17, the other being secured into the plate 18 in any manner usual for such springs, whereby said spring will have a tendency to swing or rotate the plate 18 in a certain predetermined direction.

In the embodiment shown, it is imagined that the spring 25 has a tendency to turn the plate 18 in such a manner as to have the Masonic emblem 24 on the side 23 exposed (Fig. 2).

A projection 26 may be provided at one end of the plate 18 adapted to engage a corresponding recess 27 in the frame 17 when the plate is turned in one direction whereby a rotation or swinging of the plate on the pins 19 is limited.

A similar recess 28 is provided in the opposite side of the frame 17 whereby to limit the swinging of the plate in the other direction when the projection 26 will engage this recess.

It will be seen that the plate can describe only half turn in one or in the other direction and on the respective half turns it will expose one of its two sides 21 and 23.

The frame 17 will have a downwardly curved front extension 17a which will fit into a depression 17b in the respective front side of the top

of the ring so that when the frame 17 is closed upon the top 12, it will be kept in that position by the frictional engagement between 17a and 17b, while it may be easily removed therefrom as by a finger of the user exerting an upward pull thereon.

When the frame 17 is open, rocking on its pivot 16, as indicated in Fig. 1, the plate 18 will automatically turn in one direction, in this case indicated in such a manner that the Masonic emblem 24 will be on the top of the ring when the frame 17 is closed thereon, as indicated in Fig. 2.

When it is desired to display the other side 21 of the plate and the initials 22 thereon, the user will turn the plate against the action of the spring in the opposite direction and then close the frame 17 on the top 12 where it will be kept by the frictional engagement of 17a and 17b, as has been indicated hereinbefore. By such a closure the plate 18 will be enclosed in the frame 17 and will be pressed flat on the top of the ring and will now display the initials 22.

I may also provide an upstanding curved rim 29 at the rear of the pivot 16 rising from the respective edge of the top 12 of the ring and the corresponding edge 29a of the frame 17 when the same is opened will engage the top of said curved upstanding rim 29 whereby a limit is provided for the outward swinging of the frame 17.

As will be seen I provide a reliable simple attractive original means whereby the ornamentation on the top of the ring may be changed even while the ring is on the finger of the user.

In the embodiment shown, the ring may be changed from one of an initial or sealing ring to one showing a Masonic emblem or vice versa.

As has been indicated when the frame is opened upon its pivot the spring quickly turns the plate in one direction. A small opening of the frame 17 in this case is sufficient, the action of the spring 25 will force the plate 18 against the top 12 and forces the frame to swing further until plate 18 completes a half turn, and when the frame now is closed upon the top, the respective ornament will automatically appear on the ring. All this may be done with a little initial effort and will occur extremely quickly giving the appearance of almost a magic change in the ring.

For the reverse change the frame will be opened somewhat by a finger of the user then the plate turned against the action of the spring in the opposite direction and the frame closed on the top of the ring, as has been described. A very small initial opening of the frame by a finger nail of the user is sufficient in either case and the rest will occur either automatically by the action of the spring or manually through the pressure of the user on the plate, the respective edge of the plate rubbing and pressing against the top 12 of the ring during the operation, as will be obvious.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

What I claim as new and desire to protect by Letters Patent of the United States is:

1. In a changeable ring, a top for the ring, a frame pivoted at one end of the top, a member

having two sides, rotatable in said frame, ornaments at the two sides of said member adapted to be alternately displayed upon the turning of the same, means to releasably secure said frame on said top whereby a selected side thereof will be displayed on the ring, a spring arranged between said frame and said member having a tendency to swing said member in a predetermined direction, said member having coaxial pins on which to swing, downward projections on said frame to receive said pins, and recesses in said top adapted to receive said projections.

2. In a ring, as set forth in claim 1, said spring being arranged in one of said projections around the pin therein, said projection being hollow and said spring helical.

3. In a changeable ring, a flat top for the ring, a frame pivoted at one side of the top, a plate within said frame, pivot pins for said plate in said frame, whereby said plate may rotate in said frame, predetermined designs at the two sides of the plate, means to releasably close said frame on said top whereby a selected side thereof will be displayed on the ring, downward semi-cylindrical enlargements on said frame for said pins, and recesses in said top to receive said enlargements, and a helical spring arranged in one of said enlargements around the pin therein between said frame and said plate, said spring having a tendency to rotate said plate in a predetermined direction.

4. In a ring, as set forth in claim 3, means to limit the swinging of said plate to substantially one half of a revolution in either direction.

5. In combination, a ring having a top portion, a frame pivoted to one side of the top portion and swingable from a position overlying the top portion to a position where it is swung away from said top portion, a plate bearing ornaments on opposite faces thereof, pivotally mounted about the mid-portion thereof within the frame so that said plate may be swung through an angle of 180° about its pivotal axis to expose either one or the other of its faces to the top, spring means interconnecting said plate and frame adapted to be tensioned upon swinging said plate about its pivotal axis in one direction of rotation through an angle of 180° so as to return said plate when said plate is released, through an angle of 180°.

6. The combination of claim 5, in combination with means to releasably hold the frame down against the top portion of the ring.

7. The combination of claim 6, the pivotal axis of said frame being at right angles to the axis of the ring and the pivotal axis of said plate being parallel to the pivotal axis of said frame.

8. In combination, a ring having a flat top surface, a frame pivoted to one side of said flat top surface and adapted to lie flat against said surface and adapted to be swung upwardly so as to extend at an angle to said surface, a plate within said frame and pivoted to opposite portions of the frame about an axis passing through the mid-portion of said plate and a mid-portion of said frame, said plate being adapted to be held against said flat surface when said frame is held against said flat surface, releasable means to retain said frame against said flat surface, torsion spring means interconnecting said frame and plate and adapted to be tensioned upon swinging said plate relative to said frame through an angle of 180° from normal position with one face of said plate exposed to a position where the opposite of said plate is exposed, said plate being adapted to be

held in such abnormal position when the frame is held down against said flat surface, by said releasable retaining means and whereby upon releasing said retaining means and swinging said frame upwardly away from said flat surface, said plate will be swung by said spring means automatically back to normal position.

9. The combination of claim 8, the pivotal axes of said frame and plate being parallel to each other and perpendicular to the axis of said ring. 10
